UNITED STATES PATENT OFFICE.

DONALD MACKAY, OF SPRINGFIELD, OHIO.

GOLF CLUB.

Application filed November 28, 1927. Serial No. 236,060.

This invention relates to golf clubs, it more particularly relating to a club, the head of which is provided with a metallic reinforcing plate or sole.

5 The object of my invention is to provide a sole for a golf club head so constructed and applied as to be held rigidly in position against impact or the force of inertia; also one which will afford a wide wear surface for 10 the under side of the head; and also one which will be so applied to a mortise or recess in the head as to eliminate square corners to thus obviate the tendency of the head to check or split and thereby shorten the life of the head.

15 A further object of the invention is to provide for weighting the head in such a manner that the weight is concealed and held in position in a simple and effective manner.

20 In the accompanying drawings:
Fig. 1 is a perspective view of a golf club showing my improvements applied thereto.

Fig. 2 is a bottom plan view of the same.

Fig. 3 is a section on the line *a—a* of Fig. 2.

25 Fig. 4 is an elevation of the sole plate as viewed from the heel end of the head.

Fig. 5 is a front elevation of the sole plate.

Fig. 6 is an elevation of the side edge of the sole plate as viewed from the toe of the head.

Fig. 7 is a bottom plan of the sole plate.

30 Referring to the drawings, 1 represents the head of a golf club, 2 the socket and 3 the shaft. The under surface of the head is recessed to receive a sole or wear plate 4 of peculiar construction. The side edges of this wear plate are formed on the arcs of circles; the edge 5 adjacent the heel of the head being of a smaller arc than that of the edge 6 adjacent the toe of the head due to the fact that the head from the heel to a point adjacent the toe 35 increases in width. The forward edge of this plate is formed on a substantially straight line as indicated at 7 so as to stand flush with the forward substantially flat face 7' of the head.

40 45 The under surface of the head is formed with a mortise or recess conforming to the shape of the plate, the plate being secured in the recess by a series of screws 8 which pass through openings 9 in the plate and are secured into the wood of the head, the openings 9 being countersunk to receive the heads of the screws.

Before the plate is inserted in position the head is bored at a point leading from the bottom of the recess upwardly and filled with 55 lead so as to provide a weight 10 which is completely covered and held in position by the wear plate after it has been applied.

By the arrangement described it will be seen that a wear plate is provided of a double 60 wedge-shaped character embedded in a similarly formed recess in the head so that the screws or other fastening devices are relieved from the strain of impact in the event of the forward face 7' of the plate striking the ball, 65 or from the force of inertia when the ball is struck completely by the forward face of the head. Further, it will be seen that the walls of the recess formed in the head are free from sharp corners or angles so that the danger of 70 splitting or checking is eliminated and the life of the head thus materially prolonged. Further, the shape of the plate not only enables it to be held securely against impact or the force of inertia but also affords a large 75 wear surface to protect the under surface of the head against wear from abrasion with the ground. The device is also one which can be economically manufactured and readily applied in a simple and economical manner to 80 the head of the club. The arrangement also enables the head to be weighted with a weight 85 which after the wear plate is applied is concealed from view and held from displacement.

Having thus described my invention, I claim:

In a golf club provided with a head, a metallic wear plate for the under surface of said head, said head increasing in width from the heel to a point adjacent the toe, those edges of said plate which extend in the general direction of the swinging movement of the head being of concave form by forming each edge on the arc of a circle, that edge adjacent the heel of the head being formed on a smaller arc than the other edge, said head having a recess terminating at the striking face of said head in which said plate is seated, and means for securing said plate in said recess. 100

In testimony whereof, I have hereunto set my hand this 26th day of November, 1927.

DONALD MACKAY.
